UNITED STATES PATENT OFFICE.

WILLIAM W. ANDERSON, OF NEW YORK, N. Y.

CUFF-HOLDER.

SPECIFICATION forming part of Letters Patent No. 520,552, dated May 29, 1894.

Application filed November 23, 1893. Serial No. 491,757. (No model.)

To all whom it may concern:

Be it known that I, WILLIAM W. ANDERSON, a citizen of the United States, residing at New York, in the county of New York and State of New York, have invented certain new and useful Improvements in Cuff-Holders; and I do declare the following to be a full, clear, and exact description of the invention, such as will enable others skilled in the art to which it appertains to make and use the same.

In the manufacture and use of cuff fasteners or holders, in which the shank was adapted to be connected with the cuff by an upwardly extending portion bent from the said shank and provided with a button, much difficulty has been experienced from the breaking of the device at the angle where the bend takes place. It is practically necessary, for economical purposes, that such devices be formed of thin brass. If the brass is so soft as not to be liable to break by brittleness, it will be too flexible to properly retain its shape and hold the cuff. If made sufficiently stiff for these latter purposes its temper is such that, the bend hereinbefore referred to having once been made, by the subsequent use of the device in inserting it into the button holes of stiff cuffs, and even by such manipulation of it as occurs in the manufacture—in that part of the process which consists in the polishing and finishing of the device—the great majority of the holders will be broken and rendered useless, the fracture taking place in the bend above referred to.

It is the object of my invention to produce a cuff holder of such construction as will be economical in manufacture, which can be readily attached to the cuff, and which will be strong and durable in that portion of it by which the attachment to the cuff button hole is effected.

With such object in view my improvement consists in a cuff holder comprising a strip provided with a suitable clasp, such for instance as that patented to me June 28, 1887, No. 365,662, and provided further with a supplemental strip having a broad or long base adapted to be secured upon the upper surface of the first mentioned strip, and having bent up from its intermediate portion an L or T shaped button or projection. The two ends of the said supplemental strip thus rest upon and are secured to the surface of the first

mentioned strip, and the button or securing projection adapted to engage the cuff button hole has its bend made double so as to be very strong and durable. I am thus enabled also to strengthen and render more rigid the first mentioned strip which carries the jaws for attachment to the shirt.

My improvement further consists in providing the said jaws at their rear ends with a guard of such character as will deflect any portion of the coat lining or other garment which might otherwise be caught in the rear finger piece of the spring jaws.

My improvement further consists in making the said guard and the said button or securing device in one and the same piece, and securing them together to the main body or strip of the cuff holder.

My invention further consists in the parts and combinations thereof hereinafter particularly set forth and claimed.

In order to make my improvements more clearly understood I have shown in the accompanying drawings means for carrying the same into practical effect, without however limiting my invention, in its useful applications, to the particular construction which, for the sake of illustration, I have delineated.

In said drawings—Figure 1 is a perspective view of a cuff fastener, or holder, embodying my improvements. Fig. 2 is a longitudinal sectional view of the same. Fig. 3 is a perspective view showing the two portions of my preferred form of cuff holder separated from each other.

Referring to the drawings 1 indicates a bar of suitable metal such as brass, and which in practice will be highly finished and plated with nickel or in any other suitable way. The said strip is formed with or has attached thereto suitable securing jaws 2 and 3, for instance of the character illustrated in my patent hereinbefore referred to. The rear end of the movable jaw 3 is indicated at 4, the said end constituting a thumb or finger piece by the depression of which the jaws will be separated for attachment to the shirt sleeve. The shank of the strip 1 is preferably provided with turned up edges 5 extending its full length as illustrated in the drawings.

6 is a supplemental strip or plate of metal

or other suitable substance having a long or broad base extending parallel and in contact with the upper surface of the strip 1. At its intermediate portion the said supplemental strip is bent upward to form a double shank 7, the upper end of which is further bent to form an L shaped or T shaped double head 8. The extreme end of the supplemental strip thus forms an extension 9 which is in contact with and secured to the end of the strip 1. The securing stud or button is thus formed with double bends at 10 and 11, giving it great rigidity and strength and enabling it to be repeatedly attached to and detached from the stiffest cuff without breaking at the bend. The supplemental strip is preferably made of the same width as the space between the edge flanges 5 of the strip 1, and fits neatly between the same. At suitable points the said flanges 5 are provided with extensions 12 which are adapted to be bent over and down upon the upper surface of the supplemental strip so as to secure it firmly in place. I prefer to provide the outer end or extension 13 of the supplemental strip with a finger 13 which passes through an aperture 14 in the end of the strip 1 and is adapted to be bent down closely upon the under surface of the latter.

15 is a guard attached to the strip 1 and situated at or near the end or finger piece 4 of the spring jaws. This guard is of such character as to deflect any garment which would otherwise be caught by the said finger piece. The guard is preferably made integral with and formed by bending upward and then downward the rear end of the supplemental strip, as clearly indicated in the drawings, though if found preferable the said strip 30 1 may be provided with a guard entirely independent of the stud or button. So also my improved stud or button may be employed irrespective of the said guard.

It will be observed that the base plate of the button gives great strength and rigidity 45 to the main body or strip of the holder.

What I claim is—

1. In a cuff-holder the combination with the main strip or bar having the jaw 2 and lever 3, 4, for attachment to the shirt sleeve and 50 side flanges 5, of a supplemental stiffening strip 6 fitting between said flanges, carrying the stud, and having the guarding bend 15, substantially as set forth.

2. In a cuff-holder the combination with the 55 main strip or bar having the attaching means, and side flanges 5, of the supplemental stiffening strip 6 fitting between said flanges and secured thereto at both ends, and having its intermediate portion bent up to form the stud 60 with a double shank and double button portion or head, substantially as set forth.

3. In a cuff-holder the combination with the main strip 1 having means for attachment to the sleeve, of a supplemental stiffening strip 65 secured to said main strip and having a portion intermediate between its ends bent up to form a double shank and a double flat head, substantially as set forth.

4. In a cuff holder the combination with the 70 strip 1 having the jaws 2 and 3, the finger piece 4, the upturned edge flanges 5, the extensions 12 of the said edges, of the supplemental strip having its intermediate portion resting between the said flanges 5 and engaged by the said extensions, having its end bent to form the guard, and provided with the double shanked stud, substantially as set forth.

In testimony whereof I affix my signature in 80 the presence of two witnesses.

WILLIAM W. ANDERSON.
